United States Patent Office

Des. 211,149
Patented May 21, 1968

211,149

TEXTILE FABRIC

Lester Harold Lavers and Inga Rosten Nielsen, both of 321 Water St., Vancouver 3, British Columbia, Canada

Filed May 18, 1967, Ser. No. 7,181

Claims priority, application Canada Mar. 13, 1967

Term of patent 14 years

(Cl. D92—1)

The single figure is a plan view of a textile fabric showing our new design; the design unit is contained within the dash lines, which unit is repeated in regular succession as indicated by the extensions beyond the unit boundaries.

We claim:

The ornamental design for a textile fabric, as shown and described.
